[57] CLAIM

The ornamental design for construction block faces (front
and rear), as shown and described.

DESCRIPTION

FIG. 1 is a perspective view of the construction block faces
of this invention, the portions of the block being shown in
broken lines are for illustrative purposes only and form no
part of the claimed design;

FIG. 2 is a front elevation view of the front block face of this
invention;

FIG. 3 is a side elevation of this invention;

FIG. 4 is a side elevation from the opposite of this invention;

FIG. 5 is a top plan view of this invention;

FIG. 6 is a bottom plan view of this invention; and,

FIG. 7 is a rear elevation view of the rear block face of this
invention.
